United States Patent Office

Des. 188,474
Patented July 26, 1960

188,474

CASE FOR TAPE REELS OR SIMILAR ARTICLES

Giorgio I. Spadaro, 602 N. Woodland Lane,
Northfield, Ill.

Filed Nov. 23, 1959, Ser. No. 58,425

Term of patent 14 years

(Cl. D26—14)

Fig. 1 is a perspective view of a case for tape reels or similar articles, showing my new design;

Fig. 2 is a top edge view, the bottom edge being substantially a mirror image thereof;

Fig. 3 is a side elevational view, the opposite side being substantially a mirror image thereof; and

Fig. 4 is a side edge view, the opposite side edge being substantially a mirror image thereof.

I claim:

The ornamental design for a case for tape reels or similar articles, substantially as shown and described.
